UNITED STATES PATENT OFFICE.

SAMUEL H. CAMP, OF JACKSON, MICHIGAN.

ABDOMINAL SUPPORT.

1,380,883.

Specification of Letters Patent. Patented June 7, 1921.

Application filed March 18, 1916. Serial No. 85,025.

To all whom it may concern:

Be it known that I, SAMUEL H. CAMP, a citizen of the United States of America, residing at Jackson, in the county of Jackson 5 and State of Michigan, have invented certain new and useful Improvements in Abdominal Supports, of which the following is a specification, reference being had therein to the accompanying drawings.

10 This invention relates to abdominal supports and refers more particularly to an improved construction adapted for use either in connection with a corset, or as a separate belt or support, or as an article of 15 manufacture to be sold as an attachment for corsets.

Among the objects of the invention are to provide a construction of abdominal support which is both detachable and adjustable in such a manner as to permit the wearer to conveniently put on and take off the same, and to readily adjust the pressure exerted by the support; to provide a construction of adjustment by which either 20 light or strong pressure can be applied at any predetermined part of the support; to provide an improved construction in which the lacing or lacings are so arranged and proportioned that when a given pull is exerted on the tightening strap it will produce 25 a greatly increased pull on the front section, giving an effect similar to that produced by a block and tackle arrangement; to provide an abdominal support which is adapted in 30 many instances to replace trusses or the like; to provide a construction which will properly support and reinforce the weakened abdominal walls without interfering with the normal movements of the body; 35 and in general to provide a new and improved construction of the character referred to. The invention further resides in various features of construction and in such 40 details of arrangement and combination of 45 parts as will more fully hereinafter appear.

In the drawings:

Figure 1 is a plan view showing an abdominal support embodying my invention attached to a corset;

50 Fig. 2 is a view showing the invention as applied to a support or belt;

Fig. 3 is an enlarged perspective view showing one form of adjustable lacing; and

55 Fig. 4 is a view showing the tabs arranged as a separate article of manufacture.

Describing in detail the particular con-

struction of my invention shown in the drawings, and referring first to the construction shown in Fig. 2, A designates the back or main section of the support, and B and C the side or front sections, hereinafter referred to as the tab sections. These tab sections are secured to the main section by a lacing arrangement, the particular construction of which is more clearly shown in Fig. 60 65 3 and is as follows: One end D of the lace E is secured to a strap section F, the free end of the strap section being secured by a buckle or similar device, and the lace then extends through an aperture G in the main section and through an aperture H in the tab section. After passing through the aperture H the lace is returned to the main section and passes through a second series 70 75 or row of apertures I. The manner of lacing is such that the transversely-extending portions J do not move when the strap F is pulled to draw the sections A and C toward each other. As the lacings are return-bent to extend a plurality of times across the 80 space between the edges of the sections, the movement of the strap member one inch will produce a lesser movement of the tab section toward the main section, thus giving an effect similar to that produced by a block 85 and tackle arrangement, and allowing a relatively great tension to be applied without the necessity of exerting any extremely strong pull upon the strap member. While I have shown and described a single lacing 90 95 as being so arranged as to produce this effect, the invention in certain of its aspects is not limited to the use of a single lace.

In the construction shown in Fig. 4, the tab sections B', instead of being secured to a main section, are secured to relatively narrow strips J', which are adapted to be sold as an article of manufacture to be attached to corsets of various makes, by sewing or otherwise attaching the strips J' to the body 100 of the corset.

In the construction shown in Fig. 1, it will be noticed that the clasps or buttons K which secure together the forward edges L and L' of the tab sections, are located so as 105 to come at the front of the body and correspond in position substantially with the securing members M and M' of the corset. Also the strap members N and N' are arranged to buckle or be otherwise secured at 110 the front. This arrangement allows the combined corset and abdominal support to

be conveniently applied, and avoids the necessity of the wearer stepping into either the corset or the abdominal support or pulling the support over the head.

5 Where only a slight pressure is desired the strap member F may be formed of elastic material or a portion of the sections J' may be so formed. While this arrangement would be satisfactory where the support was 10 used in cases of obesity, it is not advisable if the support is to be used in cases of hernia or the like where the safety of the person wearing the support is directly dependent on the support staying in position. In such 15 cases the strap is perfectly non-elastic and is buckled or otherwise secured at the lower part of the support, as shown in Fig. 4. Such arrangement not only generally insures the support remaining in position but 20 also produces a lifting effect which greatly relieves the strain upon the walls of the abdomen. A hook or other suitable securing device R fastened to one of the sections may also be employed for holding the support 25 in proper position, particularly where the support is worn by thin people; this catch being looped around one or more strands of the lacing or otherwise secured to hold the support and the strap in proper position.

Various other changes in the details of constructions can be made within the scope of my invention, and I therefore do not desire to limit the invention except as specified 35 in the appended claims.

What I claim as my invention is:—

1. A support, comprising a main section and a tab section, one of which has one row of eyelets and the other of which has two 40 rows of eyelets, adjustable connections between said sections comprising a lacing adapted to be looped through one row of eyelets on one of said sections and through two rows of eyelets on the other of said sections, 45 and a fastening member positioned outside of said sections and secured to said lacing, said fastening member extending toward the front of the support and adapted when drawn forward to pull the tab section rear- 50 wardly toward the main section so as to exert pressure at predetermined portions of the support.

2. A support, comprising two adjoining sections respectively provided with eyelets, 55 a lacing engaging said eyelets to adjustably connect said sections, and a tensioning member for said lacing secured to one of said sections and adjustable thereupon to vary the tension, said lacing comprising a con- 60 tinuous member having an engagement with certain of the eyelets of one of the sections restraining it against free movement and

intermediate its portions thus restrained being freely movable in eyelets of both sections and extended into engagement with said tensioning member. 65

3. A support, comprising two adjoining sections, a lacing connecting said sections, and a tensioning member for said lacing secured to one of said sections and adjustable 70 thereupon to vary the tension, said lacing comprising a continuous member having a plurality of portions, restrained against adjustment relative to one of said sections and alternating portions extending back and forth between the two sections and freely adjustable relative thereto, said alternating portions being further extended to the tensioning member and attached to the same. 75

4. A support, comprising two adjoining 80 sections, a lacing connected to said sections and a tensioning member for said lacing secured to one of said sections and adjustable thereupon to vary the tension, said lacing having a plurality of extensions to said tensioning member, a plurality of portions having an engagement with one of said sections restraining them against adjustment relative thereto and portions adjoining said extensions extending back and forth between 85 the sections and freely adjustable relative thereto, and means carried by the section engaged by the tensioning member restraining one of said extensions against deflection. 90

5. A support comprising two adjacent sections respectively provided with eyelets, a lacing engaging said eyelets to adjustably connect said sections, said lacing having a loop therein extending from the eyelets of one section, and a member to which said loop 100 is freely movably connected, adjustably engaging the other of said sections to place a tension on said lacing. 95

6. A support comprising two adjacent sections respectively provided with eyelets, a lacing engaging the eyelets to adjustably connect said sections, said lacing having a loop therein extending from the eyelets of one section, and a member adjustably engaging the other of said sections having an 110 eyelet through which said loop freely mov- 105 ably passes.

7. A support comprising two adjacent sections respectively provided with eyelets, a lacing engaging the eyelets to adjustably 115 connect said sections, said lacing being continuous and having a plurality of loops therein drawn from the eyelets of one of said sections, and a tensioning member provided with eyelets engaging said loops, said ten- 120 sioning device adjustably engaging the other of said sections.

In testimony whereof I affix my signature.
SAMUEL H. CAMP,
